H. W. SOUTHWORTH.
PULP CLEANING APPARATUS.
APPLICATION FILED JAN. 19, 1920.

1,402,456.

Patented Jan. 3, 1922.

*Inventor,
Horatio W. Southworth;*

By A. B. Upham,
Attorney.

UNITED STATES PATENT OFFICE.

HORATIO W. SOUTHWORTH, OF BROOKLYN, NEW YORK.

PULP-CLEANING APPARATUS.

1,402,456.

Specification of Letters Patent.

Patented Jan. 3, 1922.

Application filed January 19, 1920. Serial No. 352,610.

To all whom it may concern:

Be it known that I, HORATIO W. SOUTHWORTH, a citizen of the United States, and a resident of Brooklyn, in the county of Kings 5 and the State of New York, have invented certain new and useful Improvements in Pulp-Cleaning Apparatus, of which the following is a full, clear, and exact specification.

10 This invention relates to hollanders or other machinery for cleaning paper stock which is charged with ink, and my invention consists mainly in applying pressure rolls to the stock as an intermediate step in its ink 15 and dirt removing process, by means of which the ink and dirt charged stock is pressed nearly dry and is then permitted to absorb a quantity of clean water prior to its second treatment by the customary revolving 20 knives and bed plate such as are employed in hollanders.

In the drawings forming part of this specification, Fig. 1 is a plan view of a hollander having my improvements applied 25 thereto. Fig. 2 is a side sectional elevation of the same. Fig. 3 is a sectional end view thereof. Fig. 4 is a detail view of the pressure rolls showing means for giving a resilient pressure thereto.

30 In hollanders as customarily constructed, an oblong tub 1 is provided with a main shaft 2 having a driving pulley 3, a set of revolving knives 4 turned by said shaft, a bed plate 5 co-acting therewith, and two drum washers 6, the latter being separated from 35 the revolving knives and bed plate by a mid-feather 7.

I dispense with one drum washer and in the place thereof I locate two cylinders 10, 40 11, the under cylinder 10 being supported in stationary bearings held by the mid-feather and by a side of the tub 1, as shown in Fig. 3.

The upper cylinder 11 has its bearings 45 pressed down upon the lower cylinder 10 by any suitable means, as the weighted lever 13 shown in Fig. 4, in order to maintain a yielding pressure between them. Intermeshing gears 14 cause the cylinders to revolve in 50 unison, power being connected to the lower cylinder 10 through a sprocket wheel 15 and chain 16 from an electric motor 17, or other source.

Upon the upper cylinder 11 rests the edge 55 of a board or "doctor" 19, and leading up to

the juncture of the two cylinders is an inclined plane 20 up which the pulp can be guided to the cylinders. This plane is hinged, as at 23, so that it can if desired be turned up away from the floor to permit the passage 60 of the pulp beneath the cylinders. Ordinarily, however, the plane 20 is used, and in addition a block or board 21 may be secured beneath the roll 10 to make sure no pulp can pass except between the cylinders. 65

The operation of the apparatus is as follows: The dirt bearing or inky pulp and water having first been treated by the revolving knives 4 in conjunction with the plate 5, the same passes to the plane 20 and 70 follows up its surface to the rolls 10, 11 through which it is forced, forcing the ink and dirt bearing water back from the mass toward the drum washer 6 by which it is removed from the tub. The stock then meets 75 a stream of fresh water from the supply valve 22 and is carried again to the knives 4 and bed plate 5. The contact of the latter with the stock is now so light that only a separation of the fiber-mass is effected, so 80 that no injury is caused to the fibers.

In well known means for ink-extraction, reliance is placed upon the contact of the revolving knives with the bed-plate, but such contact necessitates the cutting or grinding 85 of the paper-stock so finely that the fiber is badly weakened, and much stock is lost by the fine comminution. By my process and apparatus, on the other hand, the ink-laden water is forced from the stock by the pressure of the smooth cylindrical surfaces of the rolls 10, 11, which are wholly incapable of 90 injuring the fibers. The ink-laden water being immediately removed from the tub, fresh water added to the pulp, and the knife 95 action repeated, a cleanliness is obtained for the paper stock which is impossible to former processes. At the same time, far less of the stock is rendered incapable of further use and hence less is wasted. 100

What I claim is:

1. In apparatus for cleaning paper stock from ink and other impurities, the combination with a receptacle, of beating rolls, a pair of compression rolls maintained in resilient 105 engagement one above the other, and means for their forcible rotation and for the delivery thereto of the paper stock after its treatment by said beating rolls.

2. In apparatus for cleaning paper stock 110

from ink and other impurities, the combination with a water receptacle, of beating rolls, a pair of compression rolls located one above the other with their junction line below the 5 surface of the water in the receptacle, resilient means pressing the latter rolls together, means for the forcible rotation of the latter, and means for preventing the paper stock in the water from passing the compression rolls anywhere except between them.

3. In apparatus for cleaning paper stock from ink and other impurities, the combination with a water receptacle, of beating rolls, a pair of compression rolls located within the 15 water, means for forcibly rotating the latter rolls, and means for preventing the paper stock in the water from passing the compression

rolls except as forced through between them.

4. In apparatus for cleaning paper stock from ink and other impurities, the combination with a water receptacle, of beating rolls, a pair of compression rolls located one above the other with their junction line below the level of the water, resilient means pressing the latter rolls together, means for their actuation, a doctor engaging the upper roll of said pair, and a pivoted inclined plane between the floor of the receptacle and the lower roll of said pair. 20 25 30

In testimony that I claim the foregoing invention, I have hereunto set my hand this twelfth day of January, 1920.

HORATIO W. SOUTHWORTH.
